UNITED STATES PATENT OFFICE.

WILLIAM G. KIEFER, OF BROOKLINE, MASSACHUSETTS.

ROOF PAN.

Application filed February 10, 1923. Serial No. 618,324.

To all whom it may concern:

Be it known that I, WILLIAM G. KIEFER, a citizen of the United States residing at Brookline, in the county of Norfolk and 5 State of Massachusetts, have invented certain Improvements in Roof Pans, of which the following is a full, clear, and exact description.

This invention relates to building construction and is herein shown as embodied 10 in a roof pan or down spout for draining water from a flat roof or the like.

Although a roof pan for draining a roof is needed most at the time of very heavy 15 rains or of cloudburst, it has occurred, in prior constructions, that the suddenly accumulating water has so choked the entrance to the spout that the air normally lying in the spout cannot escape. This may be due to 20 the fact that said prior constructions have straight side walls and the onrushing water tends to meet at the center of the spout and seals the air against escape. Furthermore, the area of the opening is reduced by the 25 metal in the flat strainer usually employed. It is one of the objects of this invention to provide an improved construction of roof pan which will efficiently drain water without choking the spout. In accordance with 30 this feature, the spout is made of frusto-conical shape with the result that the water tends to cling to the conical sides thus leaving, temporarily at least, a central passage for the air to escape. This also provides 35 a larger entrance area and by utilizing a strainer of dome like form the total area of the spaces between the metal need not be reduced below that of the entrance.

In prior constructions, shrinkage of timber columns or expansion of the spout or of the iron drain pipe to which it is connected, has resulted in the impairment of the joint between the spout and the drain, or between the spout and the roof line. Condensation 40 of moisture on the pipe and subsequent dripping onto plaster ceilings have also been a source of complaint. It is accordingly another object of this invention to provide an improved spout which will avoid these and 45 other undesired results. In the construction illustrated, the spout comprises an outer wall with an expansion joint and an inner wall spaced from the outer wall for its whole length to form an air chamber. These 50 and other features, objects and advantages of the invention will appear from a con-

sideration of the following specification and accompanying drawings in which—

Fig. 1 is an elevation and half section, 60 and

Fig. 2 is an enlarged section of a portion of the device.

The numeral 2 indicates a flat roof having a circular opening to receive a spout, 65 a plate 4 of sheet metal lying on the roof around the opening and having a V-shaped ring pressed into it to form a gravel guard. The plate 4 has its rim bent downwardly as at 8, laterally as at 10, upwardly again as at 12 and then it is bent back outwardly 70 as at 14 to form an annular housing surrounding the opening in the roof. The spout has an inner wall 16 of inverted frusto-conical shape, the upper edge or rim being bent outwardly as at 18, downwardly at 20 and back inwardly again at 22 to 75 form a second housing. This bent portion or bead is received in and is housed by the annular housing on the roof plate 4 and makes a tight joint therewith. 80

At the lower end of the inner wall 16 is a cylindrical extension 32 the end of which is received loosely in the upper end of a drain pipe 34. The inner wall 16 and the pipe 34 being out of contact, either can 85 expand or contract without disturbing the the other. Roof pans with a single wall cause condensation of moisture on the outside and this is objectionable. To avoid this, an outer wall 26 surrounds the inner 90 wall for its whole length and provides an air space between, which diminishes passage of heat and prevents condensation of moisture. This wall has its upper rim bent 95 outwardly as at 28 and then downwardly and inwardly at 30, the rim being housed both in the rim of the inner wall 16 and in the rim of the roof plate 4 so that a tight joint is formed. The outer wall 26 is of inverted frusto-conical shape and in two 100 sections, the lower section 36 being joined to the upper section 26 by an annular ring 38 U-shaped in cross section. The lower end of the outer wall is cylindrical as indicated at 40 and is surrounded and reinforced by a collar 42 joined to the upper end of the drain pipe 34 with a packing of oakum or the like between. Any expansion of the 105 drain pipe or the outer wall will not disturb their union on account of the expansible quality imparted by the joint at 38. A dome shaped strainer 46 having openings

is set in the mouth of the spout and anchored by the hooked anchor member 48. The metal of the spout is preferably copper and connects with a drain pipe of cast iron, wrought iron or sheet metal.

Although the invention has been described by reference to a specific embodiment, it should be understood that it is not necessarily limited thereto.

10 I claim:

1. A device of the class described having, in combination, a plate extending substantially in the plane of a roof and having an opening, an inner wall attached to 15 the plate at the rim of the opening, an outer wall attached to the plate and to the inner wall at the rim of the opening, said plate having an integral housing enclosing the ends of the inner and outer walls, and a 20 drain pipe joined to the outer wall.

2. A device of the class described having, in combination, a plate having an opening with the rim bent into a substantially closed annular housing, an inner wall in the 25 form of an inverted cone the base of which has its rim bent into the housing, and an

outer wall spaced from the inner wall and having its upper rim bent into said housing and into the bent rim of the inner wall.

3. A device of the class described having, in combination, a roof having an opening, an inner closed wall having a flange fitted to the rim of the opening and forming a housing, and an outer closed wall spaced from the inner wall and having a flange 35 enclosed within the housing of the inner wall.

4. A device of the class described having, in combination, a roof having an opening, an outer wall having its upper end 40 bent outwardly over the rim of the opening, a drain pipe receiving the lower end of the outer wall, an inner wall spaced from the outer wall and having its free depending end of smaller diameter and extending into 45 the drain pipe, said inner wall having its upper end bent outwardly over the upper end of said outer wall; substantially as described.

In testimony whereof I have signed my 50 name to this specification.

WILLIAM G. KIEFER.
